UNITED STATES PATENT OFFICE.

ANDREW C. WORLAND, OF JASPER, INDIANA.

ELECTRIC RAILROAD-GATE.

No. 827,772.

Specification of Letters Patent.

Patented Aug. 7, 1906.

Application filed April 7, 1906. Serial No. 310,568.

To all whom it may concern:

Be it known that I, ANDREW C. WORLAND, a citizen of the United States, residing at Jasper, in the county of Dubois and State of Indiana, have invented certain new and useful Improvements in Electric Railroad-Gates, of which the following is a specification.

This invention contemplates certain new and useful improvements in gates, and is particularly intended for use in connection with railroad-crossings.

The object of my invention is to provide an improved gate of this character which is movable in a perpendicular plane to both closed and open position by means of a weight, and it embodies improved electrically-controlled means for holding the weight-actuating devices in an inoperative position and for automatically releasing the same so as to allow the gate to be closed at the approach of a train and opened after the train has passed the crossing.

For a full description of the invention, reference is to be had to the following description and accompanying drawings, in which—

Figure 1 is a side elevation of my improved gate and includes also a diagrammatic view of some of the circuits employed. Fig. 2 is a perspective view of the gate. Fig. 3 is a perspective view of a portion of the weight-actuated mechanism for the gate. Fig. 4 is a detail side view of a portion of said mechanism and part of the electrically-controlled devices. Fig. 5 is a detail sectional view illustrating some of the contacts employed. Fig. 6 is a detail view illustrating one form of mechanism that may be employed for actuating the gate by means of suitable devices located in the engine-cab.

Corresponding and like parts are referred to in the following description and indicated in all the views of the drawings by the same reference characters.

Referring to the drawings, the numeral 1 designates a supporting-framework, of which one upright or standard constitutes the support for the vertically-movable gate 2, which is pivoted thereto intermediate its ends and is provided at its rear end with a counterbalance 3 in the form of a heavy iron ball or the like and with a lug 4 beyond said counterbalance. That upright of the framework 1 which carries the gate directly is preferably extended in an upward direction and constitutes the post 5. To the post 5 is connected

the revoluble shaft 6, carrying at one end a spur-pinion 7 and at its other end having a crank 8 connected to the gate 2 by means of the link-pitman 9. The pinion 7 is meshed with a gear-wheel 10, mounted at the upper end of the framework 1, and on the shaft of the wheel 10 is wound a cord or cable 11, extending up over a pulley 12 on the upright 5 and carrying an actuating-weight 13 at one end. A ratchet-and-pawl device 10^a is provided to wind up the weight 13.

The parts are so arranged that when permitted to do so the descent of the weight 13 will cause the wheel 10 to turn and likewise the pinion 7, which will revolve the crank 8. The crank 8 and its connection 9 with the gate 2 are so proportioned that a complete revolution of the crank will effect a lowering of the gate from a substantially perpendicular position to a closed horizontal position and back again, approximately one half of the revolution being sufficient to lower the gate and the other half of its revolution being sufficient to raise the gate to the open or perpendicular position. In order to hold the gate in such positions and to maintain the weight 13 in an inoperative condition, I have provided the lug 4 on the rear extremity of the gate, beyond the counterbalance 3, and in connection with said lug 4 latches 14 14', that are mounted on the framework in the proper position to be pressed by their springs 15 15' into engagement with the lug 4 at the upper and lower movements of the gate, respectively. The normal position of these latches is that in which they hold the gate from movement, and in order to release the latches so that the weight 13 may act to swing the gate I provide electromagnets 16 16', one for each latch. The latches 14 14' are within the magnetic fields of the magnets 16 16' and constitute virtually armatures therefor, so that when the circuits of which the magnets form a part are closed, as will be hereinafter described, the energization of the magnets will attract the latches and release them from the lug 4. The magnets are included in electric circuits of which the main source of supply is a battery 17 or the like, which for convenience may be located upon the post 5 of the framework, the circuits extending from said post in opposite directions from the crossing where the gate is applied by means of overhead wires 18 to telegraph-poles or similar poles, and thence to the ground and to cir-

5 circuit-closing switches 20, located between the rails. These switches 20 may be located at any desired distance from the crossing and are preferably actuated to close the circuits by means of the cow-catcher of the locomotive or suitable devices depending from the latter and preferably under the control of the engineer.

10 In the practical operation of my improved gate for railroad-crossings as a train approaches the crossing the switch 20 will be automatically actuated to close the circuit in which is included the electromagnet 16, that will attract the latch 14, holding the lug 4 with the gate in its raised or perpendicular position. Hence the said latch will be released from the lug 4 of the gate, and the weight 13 will be permitted to act to lower the gate. When the gate has been lowered, 15 the other latch 14' will engage the lug 4 and hold the gate in lowered and closed position. As the train passes the crossing the opposite switch 20 will be actuated, which will, as is manifest, close the circuit designed to release 20 that latch which holds the gate in closed position, and the weight will then be permitted to continue its downward motion to complete the revolution of the crank 8 and can swing the gate to the raised or open position.

25 In connection with the actuating means before described I have provided means for insuring the safety of a vehicle that happens to be contiguous with the crossing or between the gates at the time the approaching train automatically starts the gates to close. Such means comprise an auxiliary latch 21, which is in the present instance mounted upon the curved bar or brace 22 of the framework 1, between the latches 14 14' and preferably close to the lowermost latch. The auxiliary latch 21 is moved either to a position where it will lie in the path of the upwardly-swinging lug 4 and prevent the further closing movement of the gate or to a position where it will not obstruct the free closing movement of the gate in such manner by means of two electromagnets 23, that are included in two different circuits 24, of which the circuit-closing devices are respectively 30 located at points close to the track-rails on both sides of the same and at two other points a sufficient distance from the track-rails to insure safe passage of the vehicle in either direction. In the present instance these circuit-closing devices consist of boards 25, laid across the roadway approaching the track. From the foregoing it will be understood that as the vehicle moves across one of the boards 25 that are very close to the 35 track-rails one of the circuits will be closed and one magnet energized to throw the auxiliary latch 21 into the path of the lug 4 and momentarily prevent the further movement of the gate toward the closed position. Then 40 as the vehicle passes off the middle boards onto

the outermost boards controlling the circuit devices for the circuit of the other magnet the said other magnet will draw the auxiliary latch 21 out of the path of the lug 4 and permit the gate to be closed. It is to be noted 70 that both of the circuits for this safety mechanism are initially closed to effect their functions by means of contact-plates or brushes 26 and 27, located, respectively, on the gate near the pivot-point thereof and some adjacent stationary support. Hence these circuits can never be closed until the gate starts toward its lowered position, and by this means the circuits are under normal conditions held open, and the electric current is not wasted, 75 as it is only in effect when the train is approaching and the gate has been started toward its closed position. Under other conditions vehicles may pass freely across the boards 25 without closing either of the circuits for the auxiliary latch 21.

80 It is to be understood that, while I have shown the gate 2 and its correlated parts as on only one side of the track, in actual practice under ordinary conditions two of said gates are provided—one for each side of the track. When this is understood, the need of my safety device is at once apparent, for they effectively prevent the entrapping of a vehicle on the track between closed gates. 85

90 While I have illustrated the gate 2 as a beam solely, it is to be understood that my invention contemplates the employment of a gate proper of any desired construction.

95 As shown particularly in Fig. 6, the switches 20 may be pivotally mounted upon any suitable support and held in a neutral position by means of springs 28. Each switch 20 is provided with two oppositely-extending arms 29, designed to close the circuit in an obvious manner, and each switch is also provided with an upwardly-projecting arm 30, with which an actuating-roller 31 is 100 designed to contact to swing the switch in one direction or the other to close the circuit. 105 The roller 31 may be carried upon the beam 32, pivotally suspended from the floor 35 of the locomotive-cab and actuated by means of a foot or other lever 33, which may be locked in operative position by means of a catch 34, or it is obvious that the roller 31 may be carried by the cow-catcher of the locomotive. Preferably the brushes shown in Fig. 6 underneath the two arms 29 are yieldably 110 mounted so that they will yield when engaged by either arm 29 should the latter be pressed farther than is necessary.

115 Having thus described the invention, what is claimed as new is—

120 1. In gate mechanism for railroad-crossings, the combination of a support, a gate mounted on said support, means for automatically opening and closing said gate, electrically-controlled means for governing the opening and closing means and electric- 125 130

- ally-controlled means for automatically arresting said gate temporarily in its closing movement.
2. In gate mechanism for railroad-crossings, the combination of a support, a gate mounted on said support, means for automatically opening and closing said gate, electrically-actuated devices for controlling the gate opening and closing means, electrically-controlled means for automatically arresting said gate temporarily in its closing movement, and means whereby as the gate begins to close it will close the circuit for the electrically-controlled arresting means.
3. The combination of a support, a vertically-swinging counterbalanced gate pivotally mounted thereon, a weight-actuated gear-wheel mounted on said support, a shaft also mounted on said support and provided at one end with a pinion and at the other end with a crank, a weight-actuated cord winding on said shaft, a link connection between the gate and said crank, the gate being provided with a lug at its rear end, latches designed to engage with said lug to hold the gate in open and closed positions, electromagnets designed to retract said latches, and means for energizing said electromagnets at a distance.
4. The combination of a support, a vertically-swinging counterbalanced gate mounted thereon, weight-actuated devices designed to both close and open said gate, spring-pressed latches designed to hold said gate in

both closed and open position, electrically-controlled means for retracting said latches, and an electrically-controlled auxiliary latch designed to temporarily stop said gate in its downward movement.

5. The combination of a support, a vertically-swinging counterbalanced gate mounted thereon, means for automatically closing and opening said gate, latches designed to lock the gate in both closed and open position, electrically-controlled means for retracting said latches, an auxiliary latch and means for automatically actuating said auxiliary latch first to arrest and then to allow the closing of the gate.

6. In a gate mechanism for railroad-crossings, the combination of a support, a gate mounted on said support, means for automatically opening and closing said gate, electrically-retracted latches designed to lock said gate in both open and closed positions, an electrically-controlled auxiliary latch designed to arrest the closing movement of said gate and means whereby as it begins to close the gate will close the circuit for the auxiliary latch automatically, substantially as specified.

In testimony whereof I affix my signature in presence of two witnesses.
